His Attorney.

UNITED STATES PATENT OFFICE

163,885

AUTOMATIC CONTROLLER OR THE LIKE

Donald L. McFarland, Stratford, Conn., assignor
to General Electric Company, a corporation of
New York

Application July 22, 1950, Serial No. 11,364

Term of patent 14 years

(Cl. D26—13)

To all whom it may concern:

Be it known that I, Donald L. McFarland, a citizen of the United States, residing at Stratford, in the county of Fairfield, State of Connecticut, have invented a new, original, and ornamental Design for an Automatic Controller or the like, of which the following is a specification, reference being had to the accompanying drawing, forming a part thereof:

Fig. 1 is a perspective view of an automatic controller showing my new design; and

Fig. 2 is a side elevation of the controller shown by Fig. 1.

I claim:

The ornamental design for an automatic controller or the like, as shown.

DONALD L. McFARLAND.
